[57] CLAIM

The ornamental design for a gold separator sluice, as shown and described.

DESCRIPTION

FIG. 1 is a top plan view of a gold separator sluice, having a plurality of fixed riffles, a pair of removable internal sections, and a last chance riffle, of my new design;
FIG. 2 is a right side elevational view of FIG. 1;
FIG. 3 is a left side elevational view of FIG. 1;
FIG. 4 is a bottom plan view of FIG. 1;
FIG. 5 is a right hand end view of FIG. 1;
FIG. 6 is a left hand end view of FIG. 1; and,
FIG. 7 is a perspective view of a gold separator sluice of my new design.
